FIG. 1

FIG. 2

FIG. 1 is a front elevational view of briefs embodying my new design; and

FIG. 2 is a rear elevational view thereof.

The dominant features of the design reside in the provision of briefs having a body portion of a single color and a band of a contrasting color, said band extending around said briefs at the top edge thereof and extending from and including said top edge to said body portion, the width of said band being uniform throughout, and having vertical, narrow strips on the front of a color contrasting with said band and extending from a line joining said band and said body to and including said top edge all as shown on the drawing.

I claim:

The ornamental design for briefs, as shown and described.
